The ornamental design for a snow removal device, as shown and described.

DESCRIPTION

FIG. 1 is an environmental perspective view of a snow removal device showing my new design;

FIG. 2 is a top plan view thereof;

FIG. 3 is a right side elevational view with the left side being a mirror image thereof;

FIG. 4 is a front elevational view thereof;

FIG. 5 is a rear elevational view thereof;

FIG. 6 is a bottom view thereof; and,

FIG. 7 is an environmental perspective view thereof.

The broken line showing of the gauge in FIG. 7 is for illustrative purposes only, merely disclosing a device which can be used, and forms no part of the claimed design. The broken line showing of the human figure in FIG. 7 is for illustrative purposes only and forms no part of the claimed design.
